CLAIM

The ornamental design for a case for grinding rolling and storing smoking materials, as shown and described.

DESCRIPTION

FIG. 1 is a front isometric view of a case for grinding rolling and storing smoking materials in accordance with the new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is an exploded front isometric view of the case for grinding rolling and storing smoking materials in an open position thereof;

FIG. 9 is a front view of the case for grinding rolling and storing smoking materials in the open position thereof;

FIG. 10 is a rear view of the case for grinding rolling and storing smoking materials in the open position thereof;

FIG. 11 is a top view of the case for grinding rolling and storing smoking materials in the open position thereof;

FIG. 12 is a bottom view of the case for grinding rolling and storing smoking materials in the open position thereof;

FIG. 13 is a right side view of the case for grinding rolling and storing smoking materials in the open position thereof; and,

FIG. 14 is a left side view of the case for grinding rolling and storing smoking materials in the open position thereof.

The broken lines in the drawings depict portions of bundle of cardboard filters that form no part of the claimed design.
